UNITED STATES PATENT OFFICE.

HENRY FORD, OF DEARBORN, MICHIGAN.

DESIGN FOR A TRACTOR-DASH.

52,608.

Specification for Design.

Patented Oct. 29, 1918.

Application filed July 5, 1918. Serial No. 243,484. Term of patent 14 years.

To all whom it may concern:

Be it known that I, HENRY FORD, a citizen of the United States, residing at Dearborn, in the county of Wayne and State of Michigan, have invented a new, original, and ornamental Design for a Tractor-Dash, of which the following is a specification, reference being had to the accompanying drawing, forming part thereof.

Figure 1 is a rear elevation of a tractor dash, showing my new design;

Fig. 2 is a side elevation, and
Fig. 3 a perspective view thereof.

I claim:

The ornamental design for a tractor dash,
as shown.

HENRY FORD.
